US00D667523S

(12) **United States Design Patent**
Glimpse et al.

(10) **Patent No.:** US D667,523 S
(45) **Date of Patent:** ** Sep. 18, 2012

(54) **GUN SIGHT**

(75) Inventors: **Bryan R. Glimpse**, Trenton, MI (US);
Robert W. Condra, New Hudson, MI (US); **Joshua Lee Varner**, Commerce, MI (US); **Joseph R. Adkins**, Howell, MI (US)

(73) Assignee: **Trijicon, Inc.**, Wixom, MI (US)

(**) Term: **14 Years**

(21) Appl. No.: **29/414,221**

(22) Filed: **Feb. 27, 2012**

(57) **CLAIM**

The ornamental design for a gun sight, as shown and described.

DESCRIPTION

FIG. 1 is a front perspective view of a gun sight in accordance with the principles of the present disclosure;

FIG. 2 is a bottom perspective view of the gun sight of FIG. 1;

FIG. 3 is a rear perspective view of the gun sight of FIG. 1;

FIG. 4 is a top view of the gun sight of FIG. 1;

FIG. 5 is a side view of the gun sight of FIG. 1;

FIG. 6 is a side view of the gun sight of FIG. 1;

FIG. 7 is a rear view of the gun sight of FIG. 1; and,

FIG. 8 is a front view of the gun sight of FIG. 1.

The broken lines are for illustrative purposes only and form no part of the claimed invention.
